UNITED STATES PATENT OFFICE.

CHARLES R. HARRIS, OF WILLIAMSPORT, PENNSYLVANIA.

DESIGN FOR A SUSPENDER-BUCKLE.

SPECIFICATION forming part of Design No. 20,544, dated March 3, 1891.

Application filed January 14, 1888. Serial No. 260,786. Term of patent 7 years.

To all whom it may concern:

Be it known that I, CHARLES R. HARRIS, residing at Williamsport, in the county of Lycoming and State of Pennsylvania, have invented and produced a new and original Design for Buckles to be Used on Suspenders or Shoulder-Braces or Similar Articles, of which the following is a specification, reference being had to the accompanying drawing, forming part thereof, in which the figure represents a front face view of my new buckle design as it appears on a suspender or brace.

The principal features that I desire to protect consist of a rectangular frame A, two of the four sides of which are located vertically when in place on a suspender, as shown at A' in the figure, and substantially parallel to each other. The other two bars A² of the buckle-frame extend across the flexible material of the suspender, as shown, and join the vertical bars or sides A', the corners a being rounded to avoid sharp angles.

The material of the body of the rectangular frame A is rounded or cylindrical in cross-section. Upon the rectangular frame A of the buckle an attached clamp or bar is imposed, said bar having the configuration of a cross B. The vertical limbs B' of the crossed-bar B are in contact with the transverse por-

tions A² of the frame A, and the other limbs B² extend at right angles to the limbs B' a proper distance on each side of the same. I do not wish to limit the lateral extension of the limbs B² further than to specify that they should not project any considerable distance beyond the vertical bars A' of the frame A.

The bar B can be varied in its proportions otherwise. It is essential, however, that the limbs should be double-ribbed, as shown at a² a'.

Having fully described the conformation of parts of my design for buckles, what I claim as new, and desire to secure by Letters Patent, is-

The design for a suspender-buckle herein shown and described, consisting of a rectangular frame having rounded corners and an attached bar that represents a cross, the vertical limbs of which are in contact with the horizontal bars of the rectangular frame, the other limbs extending at right angles to the vertical limbs toward opposite sides of the rectangular frame, substantially as set forth.

CHARLES R. HARRIS.
